UNITED STATES PATENT OFFICE.

ORRIS A. HARKNESS, OF BANGOR, MAINE, ASSIGNOR TO GREAT NORTHERN PAPER COMPANY, OF MILLINOCKET, MAINE, A CORPORATION OF MAINE.

GROUSER.

Application filed September 23, 1921. Serial No. 502,758.

This invention relates to devices designed to be used on the track links of tractor treads to prevent slipping.

Tractors of this type are widely used in logging and other operations where they are required to handle heavy loads on very rough ground and in all kinds of weather. When the ground is slippery for any reason, as for instance when it is covered with ice or 5 when it is wet and contains considerable clay, the track links cannot get the same grip on the ground that they do under normal conditions, and a great deal of trouble is experienced with slipping. Obviously if 10 the links slip longitudinally or lengthwise of the track, the tractive effort or hauling power of the machine is greatly reduced. If 15 the ground traversed under these conditions is very rough or hilly, an additional difficulty is introduced by the sidewise slipping or "slewing."

With a view to overcoming these difficulties, it has been proposed heretofore to equip the track links with devices known as 20 "grousers," which are designed to prevent the longitudinal slipping of the links. While these devices may be used with more or less satisfaction under some conditions, they are far from satisfactory under severe 25 conditions, as for instance, on ground that is very rough and rocky. Under such circumstances the grousers break or drop off so frequently that they are practically useless. Furthermore, these prior constructions 30 have been of such a nature that they do not prevent the sidewise slipping of the tractor, which is fully as troublesome under some 35 conditions as the longitudinal slipping. An additional objection to grousers of the forms 40 heretofore generally used has been that they caused the track links to tip longitudinally, and this tipping movement exerts a yank on the whole track assembly.

The present invention has for its general 45 object to devise a grouser which will overcome the difficulties above mentioned and will satisfy the practical requirements for a device of this character. Stated more specifically, the invention aims to devise a 50 grouser that will prevent both sidewise and longitudinal slipping, which will be simple but sturdy and substantial in construction, economical to manufacture, can be quickly and securely fastened to the track links and

removed therefrom, and which will not be 55 liable to break or drop off.

The nature of the invention will be readily understood from the following description when read in connection with the accompanying drawings, and the novel features 60 will be particularly pointed out in the appended claims.

Referring now to the drawings,

Fig. 1 is a side elevation of a track link equipped with a grouser embodying the 65 present invention, and also including a portion of the next adjacent link;

Fig. 2 is a cross sectional view substantially on the line 2—2, Fig. 1, certain of the parts, however, being shown in elevation; 70

Fig. 3 is an angular view of an individual link;

Fig. 4 is an exploded view in perspective of the grouser provided by this invention; 75

Fig. 5 is a perspective view showing the lower side of the wedge that forms a part of this grouser.

The drawings show the invention embodied in a form designed especially for use on the track links of the Holt tractor. Each of these links has a truss-shaped body portion 2 and a tread part 3 integral with said body. The opposite sides of the tread portion of the link are grooved or recessed, as indicated 80 at 4 and 5, these grooves extending upwardly from the tread face of the link, and being inclined outwardly, as best shown in Figs. 2 and 3. The present invention utilizes this grooved construction in securing the grousers to the links. 85

The detailed construction of the grouser is best shown in Fig. 4, from which it will be seen that it includes a bar 7, having arms 8 and 9 projecting from opposite edges 90 thereof. This bar is designed to extend transversely across the tread face of the link from one side thereof to the other, as shown in Fig. 2, while the arms 8 and 9 extend longitudinally of the link, as shown 100 in Fig. 1, and the inner surfaces of these parts (that is, the surfaces which are toward the inner side of the path of travel of the links and which are uppermost in Figs. 1, 2 and 4) are shaped to conform to the portions of the tread face of the link which they engage. It will be seen that the ends 105 of the arms 8 and 9 are curved upwardly

slightly to fit the curves of the tread face of the link.

A projection 10 extends downwardly from the bottom of the bar 7 for nearly its entire length and is V-shaped in vertical cross section to form a ground engaging calk. Similar projections 12 and 13 extend downwardly from the arms 8 and 9, and form longitudinal calks; that is, they extend longitudinally of the link. The transverse calks 10 hold the links against slipping longitudinally or lengthwise of the track, and thus prevent the tractor from losing its tractive effort on slippery going, while the longitudinal calks 12 and 13 prevent the tractor from slipping or slewing sidewise. These longitudinal calks are partially cut away, as shown at 14, 14, Fig. 1, at points close to their junction with the transverse calk 10, this construction reducing the tendency of the calks to collect mud and snow; or, in other words, to "ball up".

For the purpose of securing the grouser to the tractor track link it is provided at one end with an arm 15 which is integral with the bar 7 and extends upwardly at the proper angle to fit into the groove 5 at one side of the link. A head 16 is also formed integral with this arm at the upper or inner end thereof to fit against the inclined wall 17 of the link at the upper or inner end of the groove. The bar 7 at this end also is provided with lugs 18, 18, Fig. 4, that fit snugly into the base of the groove 5. At its opposite end the grouser is provided with another lug 19, which fits snugly into the base of the groove 4, and a tapered hole 20 is formed through this end of the bar and through the lug 19 to receive the tapered shank or head of a bolt 21. This bolt extends through the groove 4 and through a hole formed in a wedge 22 which rests on the inner inclined edge 24 of the wall of the groove. The lower face of this wedge is shaped to fit the edge 24, and is provided with lugs 25, 25 at its opposite ends that extend over the outer edges of the boss or projection in which the groove 4 is formed and act to prevent movement of the wedge lengthwise of the link. The upper surface of this wedge 22 forms a flat seat to receive a nut 26 which is threaded on the bolt 21 and is locked thereon in any convenient manner, for instance, by a cotter pin 27.

It will now be appreciated that this invention provides a very simple but sturdy construction for securing the grouser to a track link. The lugs 18 and 19 fitting snugly in the bases of the grooves 5 and 4, respectively, prevent movement of the grouser in any direction parallel to the tread face of the link; while the head 16 at one end of the bar, and the bolt 21 and nut 26 at the oppo-

site end, hold the grouser firmly against the tread face of the link. I have found that by using a bolt having a tapered head or shank, as shown, the liability of this part to break is very substantially reduced; and the wedge 22 affords a very solid seat for the nut 26, so that there is no canting or tipping strain on the bolt, all the strain being exerted lengthwise of the bolt. The lugs 18 and 19 also relieve the arm 15 and bolt 21 from sheering strains to which otherwise they would be subjected by the forces tending to slide the bar over the face of the link. Since the calks extend both longitudinally and transversely of the tread face of the link and have relatively sharp edges, they effectively prevent slipping in any direction and they thus overcome the difficulties experienced in the practical use of prior forms of grousers.

While I have shown and described the invention as embodied in a grouser designed especially for use on the track links of the Holt tractor, it will be understood that the invention is not limited to use on this particular make of tractor, and that minor changes may be made in the details of the construction shown without departing from the spirit or scope of this invention.

Having thus described my invention what I desire to claim as new is:

1. A grouser for tractor track links of the type having, a groove in each side thereof, comprising a bar adapted to extend across the tread face of one of said links and shaped to fit against said face, a calk projecting from said bar, lugs at the opposite ends of said bar, rigid therewith, and shaped to fit snugly within said grooves, an arm projecting from one end of said bar and shaped to extend through one of said grooves, said arm having a head on the end thereof to rest on said link at the upper end of the groove, and a bolt extending through the end of said bar opposite to said arm and arranged to secure the latter end of said arm to the link.

2. A grouser for tractor track links of the type having a recess in the tread portion thereof, said grouser comprising a bar having a face shaped to fit against the tread face of one of said links, a lug projecting from said face to fit snugly within said recess, a calk projecting from the opposite face of said bar, means for securing said bar to one of said links, said means including a bolt having a tapered shank, said bar having a hole extending through said lug and tapered to receive said shank.

3. A grouser for tractor track links of the type having a groove in each side thereof, comprising a bar shaped to extend across the tread face of one of said links, a calk projecting from said bar, means for securing

said bar to said link, and lugs at opposite ends of said bar, rigid therewith, and shaped to fit snugly in said grooves.

4. A grouser for tractor track links of the type having a groove in one side thereof, comprising a bar shaped to extend across the tread face of the link, a calk projecting from said bar, and means for securing said bar to said link including a bolt extending through 10 one end of the bar, a nut threaded on said bolt, and a wedge-shaped part on which said nut bears, one face of said part being shaped to seat on said link at the inner end of said groove and the other face of said part forming a seat for said nut.
5. A grouser for tractor track links of the type having a groove in each side thereof, comprising a bar shaped to extend across the tread face of one of said links, calks projecting 20 from said bar and extending transversely to each other, an arm extending from one end of said bar and shaped to extend through one of said grooves, a head on the end of said arm to rest on said link at the inner end of 25 the wall of one of said grooves, a wedge having a face shaped to seat on the inner end of the opposite groove, a bolt extending through the end of said bar opposite to said arm and projecting through said wedge, a 30 nut threaded on said bolt above said wedge and lugs at the opposite ends of said bar, rigid therewith, and shaped to fit snugly in

said grooves near the tread face of the link.

6. A grouser for the track links of a tractor tread, comprising a bar designed to extend across the tread face of one of said links and having projections extending from the front and rear edges thereof, the inner surfaces of said bar and projections being shaped to fit against the tread face of the 40 link, calks projecting from the outer surfaces of said bar and projections and extending both transversely and longitudinally of the link, one of said calks being cut away adjacent to the other, and means for securing said bar to one of said links.

7. A grouser for tractor track links of the type having a groove in each side thereof, comprising a bar designed to extend across the tread face of one of said links, and having projections extending from the front and rear edges thereof, the inner surfaces of said bar and projections being adapted to fit against the tread face of the link, calks projecting from the outer surfaces of said bar 50 and projections and extending both transversely and longitudinally of the link, lugs at the opposite ends of said bar, rigid therewith, and shaped to fit snugly within said grooves, and parts connected with the opposite ends of said bar for securing said bar to one of said links.

ORRIS A. HARKNESS.
